(57) **CLAIM**

The ornamental design for a ground inserted pole support, as
shown and described.

DESCRIPTION

FIG. 1 is a perspective view of a ground inserted pole support showing my new design;

FIG. 2 is another perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is an enlarged top plan view thereof; and,

FIG. 8 is an enlarged bottom plan view thereof.

The broken lines in the drawings illustrate the portions of the
ground inserted pole support, which form no part of the
claimed design.
